UNITED STATES PATENT OFFICE.

THEODOCUS C. HAMBY, OF COLUMBIA, SOUTH CAROLINA.

CONNECTER FOR STEEL TAPES.

Application filed October 29, 1923. Serial No. 671,469.

To all whom it may concern:

Be it known that I, THEODOCUS C. HAMBY, a citizen of the United States, residing at Columbia, in the county of Richland and State of South Carolina, have invented certain new and useful Improvements in Connecters for Steel Tapes, of which the following is a specification.

This invention relates to connecting devices for holding adjacent ends of bands or tapes of metal or other relatively stiff material, and it is particularly directed to an improved form of connector for repairing steel surveying tapes.

The chief object of the invention is to provide a quick repair unit which may be readily used to effect an accurate permanent connection particularly useful for measuring tapes.

Frequently, steel bands and tapes break as result of sharp bends or sudden strain on weakened parts. Various forms of repairs have been used. Welding provides the strongest connection, but welding operations require apparatus too bulky to be carried by surveying engineers. To effect a weld repair, the broken end portion must be overlapped thus undesirably shortening the tape, or else an extra overlapping splice piece must be welded to the sides of each broken end. Heretofore, the welded repair, even with the addition of the splice piece, has been least objectionable because it did not materially thicken the tape.

Other forms of clamps and connecting devices, many of which use set screws and the like, have proved troublesome because a lumpy block often with projecting screws, prevents convenient winding or coiling of the tape and when in use, tends to catch on trees and rocks and restricts the free use of the tape.

The present device has proved useful and less troublesome than other known connections. This adaptability is possible because the connector of the present invention is comparatively thin and will lay flat when the tape is wound. One important advantage resides in the fact that there is no projection extending from the flat outside contour of the connector wall, the ultimate fastening element always lying completely within the confines of the connector both

before and after the fastening step is completed.

The above and other details and advantages will be described and claimed in the following specification and claims, and the construction illustrated in the accompanying drawing, in which:

Fig. 1 represents a top plan view of the connector illustrating how the adjacent ends of a metal tape are held together;

Fig. 2 is a longitudinal vertical section taken on the line 2—2 of Fig. 1;

Fig. 3 is a view of the bottom of the connector shown in Fig. 1;

Fig. 4 is an enlarged cross sectional view along the line 4—4 of Fig. 6, illustrating the configuration of the connector and the metal tape to be held thereby and before the fastening step is performed;

Fig. 5 is an enlarged sectional view taken on the line 5—5 of Fig. 1, illustrating the configuration of the upper face of the connector and the metal tape after the structure of Fig. 4 has been changed, and the fastening step completed; and

Fig. 6 represents a top plan view of the connector block shown in Fig. 1 but before the block has been deformed to fasten the end portions of the metal tape in position.

Like reference characters identify like parts in the different figures of the drawing.

Referring in detail to the drawing, 1 is a long flat body block of relatively rigid metal which is capable of being deformed under severe blows but which resists wear and tear to which surveying tapes may be subjected. This body block may be formed of brass or a hard copper alloy. The block is designed to receive and hold securely the adjacent ends of a broken metal tape indicated at 2 and 3. The top of the body block, as shown in Fig. 1, has an upper wall 1^a which is imperforate except for a central opening through which the position of the extreme ends 2^a and 3^a of the metal tapes may be viewed. The opposite or under face of the body block is shown in Figs. 2, 3, 4 and 5 as 1^b. Extending lengthwise through the body block is a slotted opening having an edge wall 1^c which latter, together with the opposite inner upper and lower faces, is adapted to closely embrace and securely hold against

perceptible edgewise movement, the adjacent tape portions.

For locking the tape portions in the connector, the invention contemplates a riveting operation in which the upper wall 1^a of the body block is deformed downwardly to correspondingly deform the metal tape in accordance with the following explanation.

At the points indicated at 4, the upper surface 10 face 1^a is adapted to be driven downwardly by the action of a suitable punch driven sharply by a hammer blow. The under face 1^b is provided with openings 6, located opposite to the points 4 of the upper surface

15 and spaced inwardly from the ends of the body block. Thus, when the upper surface is deformed downwardly, it serves to depress both the upper surface 1^a at the points 4 and also the tape portions 2 and 3 at the

20 respective points 2^b and 3^b. The result is illustrated in Fig. 2 which shows the upper wall 1^a and the tape portions 2^b and 3^b extending downwardly into the openings 6 in the lower wall of the body block. Figure

25 4 represents the structure in cross section at one of the openings before the upper face is depressed and Figure 5 is a corresponding view showing the positions taken by the upper wall and the metal tape after the deforming or fastening operation is completed.

The sight opening 5 serves to assist in making certain that the opposite adjacent ends actually touch, and thus the tape may be accurately repaired and without changing the length materially. If the sight opening 5 was not provided, there is a possibility that some obstruction might become lodged between the adjacent ends, thus separating them and preventing accurate repairs.

40 Most metal tapes are of spring steel and when such material is deformed into the position illustrated in Figures 2 and 5, it will retain that position and effectively prevent the withdrawal of the tape from the body block. It will thus be seen that this connector element is self contained in that it has no projecting fastening screws or bolts which might become caught on objects and thus interfere with the free use of the tape

45 on which the repair has been made. The invention is capable of being used in the joining of any material which may be deformed by the depression of one wall of the body block to correspondingly depress the 50 material held into an opening on the opposite side of the body block from which the depression is formed. Changes in material may be made without departing from the scope of the invention so long as the material 55 is capable of remaining in the shape to which the fastening operation has changed it.

I claim:

1. In a connector, a body block having main openings extending inwardly from its 60 opposite ends for the reception of the ends

of articles to be secured, said body block having lateral openings through the wall thereof and extending from the exterior into said main openings, and the wall of said body block opposite to said lateral 70 openings being solid and imperforate and of rigid material capable of being deformed toward said lateral openings and to remain fixedly in the deformed position, and the sides of said walls at either side of said 75 lateral openings and throughout the length of the block between said main openings being continuous and providing continuous supporting contact for the articles to be held against movement in a plane at right 80 angles to said lateral openings.

2. A device for holding the adjacent broken end portions of metal tapes comprising a body block of rigid metal having a flat slotted opening therethrough with continuous edge walls adapted to closely receive the ends of a metal tape, said body block having lateral openings through the wall thereof and at right angles to the flat dimension and extending from the exterior into said slotted opening, and the wall of said body block opposite to said lateral 85 openings being solid and imperforate and of rigid material capable of being deformed toward said lateral openings and to remain 95 fixedly in the deformed position.

3. A device for holding the adjacent broken end portions of metal tapes comprising a body block of rigid metal having a flat slotted opening therein adapted to closely receive the ends of a metal tape, said body block having lateral openings through the wall thereof and extending from the exterior into said slotted opening, and the wall of said body block opposite to said lateral 100 openings being solid and imperforate and of rigid material capable of being deformed toward said lateral openings and to remain 105 fixedly in the deformed position, said block also having a sight opening through the wall thereof and communicating with said slotted opening and located between said lateral openings and through which the adjacent tape ends may be viewed.

4. The combination of a two part metal 115 tape and a device for holding the two parts in fixed relation to each other comprising a body block of rigid material having a slotted opening extending inwardly from the ends, a separate piece of metal tape extending into each opposite end into said slotted opening, the side wall in said slotted opening closely embracing said tape ends and conforming to the shape thereof, said body block having lateral openings through the wall thereof and extending from the exterior into said slotted opening, and the wall of said body block opposite to said lateral 120 openings being solid and imperforate and of rigid material deformed toward said 125

130

lateral openings and capable of remaining fixedly in the deformed position, and each of said tape end portions having a deformed portion extending into its respective adjacent lateral opening on one side of the tape and on the opposite side receiving the complementary deformed portion of the body

block wall, said body block providing adjacent the edges of said pieces of tape continuous supporting contact on both faces of 10 the tape adjacent its edges and along the edges thereof.

In testimony whereof I affix my signature.
THEODOCUS C. HAMBY.
